UNITED STATES PATENT OFFICE.

PETER H. ROUILLARD, OF SPRINGFIELD, MASSACHUSETTS, ASSIGNOR TO ROUILLARD TOOL CORPORATION, OF PHILADELPHIA, PENNSYLVANIA, A CORPORATION OF PENNSYLVANIA.

TOOL-HOLDER.

1,355,698.

Specification of Letters Patent.

Patented Oct. 12, 1920.

Application filed June 13, 1919. Serial No. 303,896.

To all whom it may concern:

Be it known that I, PETER H. ROUILLARD, a citizen of the United States of America, residing at Springfield, in the county of 5 Hampden and State of Massachusetts, have invented a new and useful Tool-Holder, of which the following is a specification.

My invention relates to improvements in holders for various tools used in connection 10 with lathes, boring mills, shapers, planers, and the like, and consists essentially of a one-piece member having one terminal bent at an angle to the line of direction of the main body portion of said member, and having 15 tool-receiving passages at the terminals, which passages are of peculiar shape in cross-section, and provided with set-screws for securely holding such tools in said passages, all as hereinafter set forth.

20 The primary object of my invention is to provide a comparatively simple and inexpensive, compact, strong and durable holder with which metal-cutting tools of different kinds and shapes may be securely connected 25 and in which they may be held in proper position while operating on the work, it being understood that this holder is intended to be secured to the tool-post or other similar device of the machine with which 30 the holder is used.

Another object is to furnish such holder with binding means for the tools which means are of such a nature as to avoid breaking the same. Such means consist of 35 set-screws disposed in opposite edges of the shank so that they bear on the top and bottom of the tool between. Heretofore in a holder of this type a single set-screw for each tool has been employed, with the result 40 that the tool has been broken by the set-screw when the former has a deflection therein and is forced down by the set-screw on to a flat surface, the concavity in the tool being contiguous to such surfaces.

45 Other objects and advantages will appear in the course of the following description.

I attain the objects and secure the advantages of my invention by the means illustrated in the accompanying drawings, 50 in which—

Figure 1 is an elevation of one side of a tool holder which embodies a practical form of my invention; Fig. 2, an elevation of the opposite side of said holder; Fig. 3, an elevation of one edge of the holder showing a

straight, square tool or cutter attached thereto; Fig. 4, a longitudinal section through the holder extending from end to end and with said cutter in position, such section being taken through the center of 60 the edges of the holder; Fig. 5, an edge elevation of the holder, similar to that shown in Fig. 3, having a left-hand, square cutter attached thereto; Fig. 6, an elevation of the opposite edge of the holder having a right-hand, square cutter attached thereto; Fig. 65 7, a similar elevation showing a boring tool in place, said tool being octagonal in cross-section; Fig. 8, an edge elevation similar to that shown in Fig. 3, but having a straight, 70 round cutter connected with the holder; Fig. 9, still another similar elevation, but with a nurling-tool in place of either the square or round cutter; Fig. 10, an elevation of one end of the holder, Fig. 11, an 75 elevation of the other end of said holder, and, Fig. 12 a longitudinal section similar to that shown in Fig. 4, but illustrating a slightly modified construction.

Similar numerals refer to similar parts 80 throughout the several views.

Referring to the drawings it will be observed that the holder consists of a shank having a straight body part 1 and an integral, bent part 2, said part 1 having a 85 passage 3 therein and said part 2 having a passage 4 therein, and a plurality of set-screws 5. The part 2 is bent at an angle to the line of direction of the body part or portion 1 of the holder, the offset being on one 90 side of said holder.

Each of the passages 3 and 4 has square corners with concave sides, in cross-section, as best represented at 6 and 7, respectively, in Figs. 10 and 11. The purpose of giving 95 this form to the passages 3 and 4 is to enable them to receive tools or cutters which have shanks that are round, square, or of other angularity in cross-section, and to enable such tools to be held securely in place, in the 100 manner and by the means presently to be described.

The passage 3 may extend into the body portion 1, from the free end of such portion, at an angle so as to give the proper incline 105 to the tool which may be received in such passage. Or, a corresponding passage, as 13 in Fig. 12, may be provided, which has the same axis as the longitudinal axis of the body portion of the holder.

The passage 4 extends through the bent part 2 opening through the free end of such part and through the side of the portion or body 1 which is opposite to that on which said part 2 is located.

One of the set-screws 5 is tapped through one edge of the body 1 and is capable of being turned down so that it projects into the passage 3. Two of the set-screws 5 are 10 tapped into opposite edges of the bent part 2, their axes are in the same straight line, and said set-screws are capable of being turned inwardly until they project into the passage 4. The set-screws 5 are without 15 heads, but have angular sockets opening through their outer ends to receive an implement or wrench, such as that shown at 9 in Fig. 4, for the purpose of tightening and loosening said screws.

20 Referring to Figs. 3 and 4 it will be seen that I therein show a square cutter 10 for making a "straight" cut. The cutter 10 is received in the passage 3, fits more or less loosely within the rectangular corners 25 6 of said passage, and is secured by means of the set-screw 5 when the latter is turned down, by means of the implement 9, tightly against said cutter. The cutter 10 has a forward and upward inclination, owing to the 30 inclination of the passage 3 relative to the body 1, when the holder is held in proper position, and the set-screw 5 with which said cutter is secured is then above the latter and engages the top thereof.

35 In a similar manner a round cutter, as 11, shown in Fig. 8, is attached to the holder, or the shank of a nurling-tool, as 12, shown in Fig. 9, is attached to said holder. In each of these cases the cylindrical portion 40 of the cutter 11 or of the nurling-tool 12 is received in and fits more or less loosely the concave sides 7 of the passage 3. Not only is the member in the passage 3 held securely by means of the concave sides 7 and the contiguous set-screw 5, but provision is thus 45 made for very nice adjustment about its own axis of such member.

The passage 4 in the offset part 2, the 50 axis of which said passage is the same as the axis of said part, is adapted to receive either a square or round "right-" or "left-hand" cutter, such tool being secured by means of the two set-screws 5 with which said part is provided. The set-screws 5, in this case, 55 engage the cutter from above and below and securely hold the same in place without liability of breakage. The square cutter is received in the corners 6 and the round cutter in the concave sides 7, as in the first case. 60 In Fig. 5 a square cutter 14 is shown in the holder and the parts are positioned to make a left-hand cut, while in Fig. 6 the holder is turned over and the parts are in position to make a right-hand cut. The same cutter 65 14 may be used here provided it be first

removed from the holder, turned over, and reengaged therewith. A round cutter may be substituted for the square cutter 14, just as the round cutter 11 may be substituted for the square cutter 10, and adjusted about 70 its axis. A boring tool 15, having a shank which is octagonal in cross-section, is shown in Fig. 7 as being connected with the holder. The boring tool 15 is inserted in the passage 4 from the free end of the bent 75 part 2, and secured by means of the two set-screws 5 in said part. The shape of the passage 4 is adapted to receive and securely hold, with the aid of the set-screws, the boring tool 15 as well as any other tool, as will 80 be readily seen.

It is due to the bent part 2 that the holder may be inverted so as to use the same either as a right- or left-hand holder.

The holder illustrated in Fig. 12 is similar to the other holder except with regard to the passage 13 and in that there are four set-screws 5 at each end. This construction is advantageous in a large holder more especially, for the reason that the straight cutter 90 is held at the top and bottom by two pairs of set-screws, and likewise with regard to the cutter or implement at the other end. The cutter in the passage 13, being held by the aforesaid set-screws out of contact with either the top or bottom of said passage, is not likely to be broken, the same thing being true, of course, with regard to the cutter or member in the passage 4 in any case. Obviously two oppositely-disposed set-screws 100 might be used alone in connection with the passage 13, and, furthermore, a set-screw might be added to the holder hereinbefore first described to coöperate with the other in connection with the passage 3.

105 It is to be noted that the set-screw 5 which protrudes into the passage 3 is arranged with its axis at right-angles to the axis of said passage.

This tool holder can be used to take the 110 place of four different tool holders, namely, a straight tool holder, a right-hand tool holder, a left-hand tool holder, and a boring tool holder, and is adapted also to retain for practical use quite a large number of different tools or cutters.

115 An important feature of this invention is that the parts are combined in one piece, with the exception of the set-screws, which piece can be forged from a bar of solid metal 120 or malleable steel, the passages 3 (or 13) and 4 can be bored and broached in the usual manner, and the openings for the set-screws 5 can be tapped also in the usual manner.

125 By using the headless, socket set-screws 5 my holder is free from projections which are objectionable for various reasons in a device of this character.

130 Various changes in the shape, size, and minor details of construction may be made

without departing from the spirit of my invention or exceeding the scope of what is claimed.

What I claim as my invention, and desire 5 to secure by Letters Patent, is—

1. As an improved article of manufacture, a tool holder comprising a body portion and a bent part at one terminal of such portion, said body portion and bent part having 10 therein tool-receiving passages, said passage in said body portion having square corners and concave sides in cross-section, and set-screws tapped into said body portion and said bent part to engage tools therein.
- 15 2. As an improved article of manufacture, a tool holder comprising a body portion and a bent part at one end thereof, said body portion and bent part having tool-receiving

passages therein, said passage in said bent part having square corners and concave sides 20 in cross-section, and set-screws tapped into said body portion and said bent part to engage tools therein.

3. As an improved article of manufacture, a tool holder comprising a body portion and a bent part at one terminal thereof, said body portion and said bent part having 25 therein tool-receiving passages, said passages having square corners and concave sides in cross-section, and set-screws tapped 30 into said body portion and said bent part to engage tools therein.

PETER H. ROUILLARD.
